UNITED STATES PATENT OFFICE.

WILLIAM RODGER, OF ST. PAUL, MINNESOTA.

CIGAR-WRAPPER-CUTTING MACHINE.

SPECIFICATION forming part of Letters Patent No. 319,424, dated June 2, 1885.

Application filed July 24, 1884. (No model.)

To all whom it may concern:

Be it known that I, WILLIAM RODGER, a citizen of the United States, and a resident of St. Paul, in the county of Ramsey and State 5 of Minnesota, have invented certain new and useful Improvements in Cigar-Wrapper-Cutting Machines, of which the following is a specification.

In the drawings, Figure 1 is a sectional side 10 elevation, Fig. 2 is a front elevation, and Fig. 3 is a plan view, of the machine. Figs. 4 and 5 are enlarged perspective detail views of portions of the feed mechanism detached, and Fig. 6 is a side view of the machine complete.

15 A is the base or table, on which the hollow cutter B is secured, the latter being formed in the ordinary manner to cut a wrapper of the required form from a leaf of tobacco.

20 C is a standard on the rear of the base A, and having pivoted in its upper end a lever-arm, D. This lever-arm is provided on one end with a flat metal plate, E, and on the other end with a counter-weight, F, as shown.

25 Secured to the under side of the plate E is a mallet or hammer, E', of hard rubber or other suitable material, adapted to strike the top of the cutter or knife B when the lever-arm D is raised and lowered to cut the wrapper out of the leaf, which is stretched over the cutter.

30 A thin strip of soft rubber, hard paper, or other similar suitable flexible material, t, is interposed between the plate E' and mallet E', around the outer edge, leaving a hollow space in the center between the plate and mallet, as 35 shown in Fig. 1.

Small holes b are bored through the mallet E', connecting the hollow space formed by the strip t with the interior of the cutter B, the holes ending near the cutting-edge of the knife, 40 and will usually be formed slanting outward, as shown.

The flexible strip t serves a double purpose—viz., forming the open space between the mallet E' and plate E', and also serving as a cushion 45 to deaden the force of the blow upon the plate E' and lever D.

H is a small cylinder pivotally attached by ears c to the lever-arm D, and connected at its upper part by a flexible tube, K, with a hollow 50 stud on top of the plate E', the interior of the cutting-knife B thus being in direct communication with the interior of the cylinder H when

the mallet is in contact with the cutter, as shown in Figs. 1, 2, and 3.

The upper part of the cylinder H is provided 55 with small ports or perforations d, covered on the under side with a downwardly-opening valve, e, and having a piston-head, L, moving up and down in its interior. To this piston is attached an operating-rod, M, which is moved 60 upward by a foot-treadle, M', attached thereto, and a spring, g, is provided by which the piston will be returned to the bottom of the cylinder at the completion of each stroke.

Inside the cutter B is a follower-plate, N', 65 conforming to its interior, and having a rod, N'', running from its center down through the table A, as shown.

After being stretched over the cutter and the wrapper cut out, the cut wrapper is liable to 70 shrink and curl up, and to prevent this is the object of the follower-plate N', which holds the cut wrappers pressed up against the mallet and prevents them curling or shrinking. The 75 only time when the pressure is removed is the short interval of time when the mallet is raised and another leaf is stretched over the cutter.

I have shown two methods of holding the follower-plate N' upward, one a simple friction-spring, N³, which will allow the rod N² 80 to slip through it as the wrappers accumulate in the cutter, and force the follower-plate down, each blow of the mallet forcing the follower down the thickness of one leaf. A tension-screw, i, will be arranged in the spring N³ to regulate the force of the spring and to 85 take up wear on the rod.

The other method of holding the follower-plate consists of a split spring-lever, N⁴, 90 adapted to be moved up and down on a fixed tapered standard, N⁵, by a rod, N⁶, connecting it with the treadle-rod M, the joint between the rod N⁶ and lever N⁴ being a "knuckle" or "rule" joint, so that the lever N⁴ is operated only at the last portion of the stroke of 95 the treadle. By delicate adjustment of the rod M by the screw-adjustment m, the throw of the spring-lever N⁴ at each stroke may be made equal to just the thickness of a leaf of tobacco.

When the spring-lever N⁴ moves upward, it will be spread apart by the taper of the standard N⁵, and release its grip on the rod N⁶ and not move it; but when moving down again the 100

decrease of thickness of the standard will permit the lever to clamp the rod N^2 and move it downward the thickness of a leaf of tobacco.

I prefer the friction-tension shown at N^3 , as 5 being more simple and operating perfectly.

The operation is as follows: The lever-arm D and its attached mallet E^2 are raised by the rod M, and held elevated till a leaf of tobacco is stretched over the cutter B. Then the force 10 applied to the rod is withdrawn, and the mallet, falling by its own weight, cuts a wrapper out of the leaf the shape of the cutter B. The mallet is then raised again, the action of raising the rod M causing the piston L to run up 15 into the cylinder H and force a current of air through the tube K into the cavity between the plate E' and mallet E^2 , and thence through the perforations b, against the outer edge of the cut wrapper, and blow it loose from 20 the mallet and force it down into the cutter B upon the follower-plate N' , and thus prevent it adhering to the mallet. The follower-plate N' will be pushed up to the upper edge 25 of the cutter B before the first wrapper is cut, and as fast as the wrappers are cut the follower will be forced down, as before described. When the cutter is full of wrappers, (which will usually hold about one hundred,) the mallet is raised, and the follower-plate pushed up 30 by the rod N^2 from below, which will cause the wrappers to appear above the cutter, so that they can be removed bodily, and avoid the necessity of handling each separately.

The power of the spring g will be so adjusted that the piston L will be moved upward 35 into the cylinder H a sufficient distance to compress the air therein to the required extent to force the cut wrapper loose from the mallet before the compression is sufficient to overcome 40 the weight of the lever D and its attachments, so that the compression of the air will be present to force the wrapper loose from the mallet just as soon as the mallet begins to rise. The power of the spring g will also be so adjusted 45 that it will be compressed to an extent equal to the required stroke of the piston-head L before the inertia of the lever D and its attachments will be overcome.

The counter-weight F will be adjusted to regulate 50 the force of the blow of the mallet, so as not to injure the cutter B by too hard blows, and equalize the strains and render the operation easier.

Having thus described my invention and set 55 forth its merits, what I claim as new is—

1. In a cigar-wrapper-cutting machine, a

fixed cutter, a rising and falling lever, and perforated mallet attached to said lever and operating in connection with said cutter, in combination with pneumatic appliances connected 60 with said perforated mallet, which force a current of air down through the perforations in said mallet, substantially as set forth, whereby the cut wrappers are prevented from being lifted from said fixed cutter. 65

2. A fixed cutter, a rising and falling lever, and a perforated mallet attached to said lever and operating in connection with said cutter, in combination with a cylinder attached to said lever, a tube connecting said cylinder and perforated mallet, a piston which works in said cylinder, and an operating-rod connected to said piston, substantially as set forth, whereby the upward movement of the mallet is effected simultaneously with the forcing of the air 75 through the perforations in said mallet. 70

3. The combination of the fixed cutter B, lever D, carrying the perforated mallet E^2 , cylinder H, provided with valve e, and pivoted to said lever, tube K, connecting said cylinder and mallet, and connecting-rod M, having piston-head L working in said cylinder, substantially as hereinbefore shown and described. 75

4. The fixed cutter B, and the rising and falling lever D, in combination with a plate, E' , 85 fixed to said lever, a perforated mallet, E^2 , attached to said plate, and a strip of flexible material, t, between the respective edges of the plate and mallet, whereby an inclosed space is left between said plate and mallet, with which 90 space the perforations in said mallet communicate, substantially as set forth. 95

5. The cutter B, the follower-plate N' in said cutter, and the rod N^2 , attached to the bottom of said follower-plate, in combination with the 95 tapered standard N^5 and the split spring-lever N^4 , pivoted to said standard and applied to said rod N^2 , substantially as set forth. 100

6. Rising and falling lever D, mallet E^2 , operating-rod M, cutter B, follower-plate N' , rod N^2 , tapered standard N^5 , and split spring-lever N^4 , in combination with adjustable collar m on 105 said rod M, and a connecting-rod, N^6 , pivoted to said collar and connected with said lever N^4 by a knuckle-joint, substantially as set forth. 110

In testimony whereof I have set my hand in the presence of two subscribing witnesses.

WILLIAM RODGER.
